PROTECTIVE HOUSING FOR ENCASED METERS

Clyde Shuler, Media, and Charles J. Godfrey, Philadelphia, Pa., assignors to Fox Products Company, Philadelphia, Pa., a corporation of Pennsylvania

Application August 11, 1952, Serial No. 20,971

Term of patent 14 years

(Cl. D52—1)

To all whom it may concern:

Be it known that we, Clyde Shuler and Charles J. Godfrey, citizens of the United States and residents of Media, in the county of Delaware, and Philadelphia, in the county of Philadelphia, and State of Pennsylvania, respectively, have invented a new, original, and ornamental Design for a Protective Housing for Encased Meters, of which the following is a specification, reference being had to the accompanying drawings, forming a part thereof.

Fig. 1 is a front elevational view of a protective housing for encased meters embodying our new design;

Fig. 2 is a side elevational view thereof;

Fig. 3 is a top view thereof;

Fig. 4 is a rear elevational view thereof, and Fig. 5 is a vertical sectional view taken on the line 5—5, Fig. 1.

We claim:

The ornamental design for a protective housing for encased meters, substantially as shown.

CLYDE SHULER.

CHARLES J. GODFREY.
